(57) **CLAIM**

The ornamental design for an integrated cabinet for energy storage as shown and described.

DESCRIPTION

FIG. 1 is a front view of an integrated cabinet for energy storage showing our new design;

FIG. 2 is a rear view thereof;

FIG. 3 is a left view thereof;

FIG. 4 is a right view thereof;

FIG. 5 is a top view thereof;

FIG. 6 is a bottom view thereof;

FIG. 7 is perspective view thereof;

FIG. 8 is an enlarged view showing portion 8 in FIG. 1;

FIG. 9 is an enlarged view showing portion 9 in FIG. 7;

FIG. 10 is an enlarged view showing portion 1A in FIG. 1;

FIG. 11 is an enlarged view showing portion 1B in FIG. 1;

FIG. 12 is an enlarged view showing portion 1C in FIG. 1;

FIG. 13 is an enlarged view showing portion 1D in FIG. 1; and,

FIG. 14 is an enlarged view showing portion 7A in FIG. 7.

The broken lines in the drawings depict portions of the integrated cabinet for energy storage that form no part of the claimed design.

1 Claim, 14 Drawing Sheets
